UNITED STATES PATENT OFFICE.

EINAR G. KNIERIEM, OF WESTCHESTER, NEW YORK.

CLOTH-STRETCHING ROLLER.

1,205,905.

Specification of Letters Patent. Patented Nov. 21, 1916.

Application filed October 11, 1915. Serial No. 55,316.

To all whom it may concern:

Be it known that I, EINAR G. KNIERIEM, a subject of the King of Denmark, residing at Westchester, in the county of New York and State of New York, have invented certain new and useful Improvements in Cloth-Stretching Rollers; and I do hereby declare the following to be a full, clear, and exact description of the invention, such as will enable others skilled in the art to which it appertains to make and use the same.

This invention relates to stretching rollers for fabric for use in textile mills and it has for an object to provide an improved type of roller in which the longitudinally moving slats are so mounted as to provide for the proper lubrication thereof, and also to have said slats actuated by a cam in which two-thirds of the revolution of said bars about said cam is consumed to gradually move said bars from one limit of movement to the other and the other third of the revolution about said cam serves to abruptly return said bars to their initial position.

Further objects of this invention is the provision of improved means for mounting the slats comprising the roller upon the shaft to permit easy removal of any of the slats and to also furnish rugged construction to withstand the wear and tear of such a roller.

Further objects will be apparent from the following specification, appended claim and drawings, thereof, in which—

Figure 1 is a composite sectional view and elevation of the roller made in accordance with this invention, Fig. 2 is a cross sectional view as on the line 2—2 of Fig. 1, Fig. 3 is a bottom view of one of the bearing blocks, Fig. 4 is a sectional view therethrough, as on the line 4—4 of Fig. 3, Fig. 5 is an end elevation of said block, and, Fig. 6 is a detailed sectional view as on the line 6—6 of Fig. 2.

Referring to the drawings in which similar reference numerals indicate similar parts throughout the several views, there are shown standards 10 which may be those commonly used in machines of this character and supported by these standards are the hubs 11 which may be held against rotation and in adjusted position as by the set screws 12. These hubs support the cams 13 which will preferably be of special design to exert the limit of throw in two-thirds of the circumference thereof, and the return

stroke in the remaining one-third to thereby more effectively stretch the fabric during the gradual movement of said cam through the two-thirds of revolution of the members to be hereinafter described about said cam. 60 The hubs 11 support the rotatable shaft 14 which has the reduced ends 15 which form shoulders to engage the hubs 11 and limit the longitudinal movement of said shafts.

The shaft 14 supports a number of heads 65 16 which may be securely held in place as by set screws or the like 17, and each of these heads has a plurality of fingers 18 carried thereby to support bearing blocks 19 to which the slats 20 are connected in any desired manner. The bearing blocks 19 have ears 21 formed thereon which are recessed as at 22 to receive the pins 18 and between the ears 21 is a space 23 which is adapted to receive a felt washer 24 which is saturated 75 with the lubricant to afford the proper lubrication for said bearing blocks on said pins. These bearing blocks have bearing faces 25 which are formed by the central recessed portion 26 and the bearing faces 25 80 are adapted to engage the peripheries of the heads 16. These bearing faces are also provided with the ribs 27 which engage grooved portions 28 in the slats 20.

The end bearing blocks have the stems 85 29 which extend beyond the ends of the slats 20 and have the heads 30 formed thereon, which are provided with the threaded openings 31 to receive the screws 32 to support rollers 33 which are disposed between the 90 side walls of the cam 13 as shown. It is clearly seen that by the removal of the screw 32, the slat from which said screw was removed indirectly through the bearing block may be easily removed from the roller by 95 sliding said slat longitudinally from engagement with the pins 18 which support the same.

As the roller is formed of a plurality of slats of which those on the opposite sides of the center move in opposite directions, provision is made for maintaining substantially a continuous surface between the slats and to accomplish this, the adjacent ends of the slats are halved together to provide the necessary movement for each of the slats in a straight line. In order that these slats may have the desired gripping action on the fabric passing about said roller, each slat is provided with a metallic face 34 which is 110

serrated or ribbed obliquely having the abrupt edges of the serrated face directed from the center of the roller.

It is clearly seen that the felt washers 24 afford ample lubrication for the sliding movement of said slats and said felt washer retains a sufficient quantity of lubricant to sufficiently lubricate the moving faces over an extended period and furthermore, no excess lubricant is present to be thrown upon the fabric as by a centrifugal force in the rotation of the roller. The rollers 33 and cam 13 are disposed beyond the ends of the slats 20 so that said rollers and cam faces may be frequently lubricated. In being disposed beyond the ends of the roller, it is impossible for any lubricant being thrown or conveyed from these faces to the fabric being treated. The shaft 15 will operate as in common practice, and it is apparent that the action of the slats to the opposite sides of the center is balanced so that no end thrust occurs when the machine is in operation as the opposite ends pull proportionately by the cams 13.

Various modifications may be made within the scope of this invention without departing from the spirit thereof and the drawings are submitted for illustrative purposes only.

Having thus described my invention, I claim:

A cloth-stretching roller comprising a shaft, heads on the shaft, guide-pins on the heads, two sets of slats forming the periphery of the roller, bearing blocks attached to the slats and slideable on the guide-pins and heads for sliding the slats longitudinally of the roller, grooved cams at each end of the roller, one for each set of slats, rollers in the grooves, and pins on the bearing-blocks, and engaging the rollers, whereby the slats may be slid off the roller upon removal of the screws.

In testimony whereof I affix my signature in presence of two witnesses.

EINAR G. KNIERIEM.

Witnesses:

HARRY C. ADAMS,
GEORGE L. THOM.
